poration of Michigan

Application April 9, 1954, Serial No. 29,938

Term of patent 7 years

(Cl. D14—6)

To all whom it may concern:

Be it known that I, Frederick Gordon Mackay, a citizen of the United States and a resident of the city of Detroit, in the county of Wayne and State of Michigan, have invented a new, original, and ornamental Design for a Bumper Guard, of which the following is a specification, reference being had to the accompanying drawing, forming a part thereof.

On the drawing:

I claim:

The ornamental design for a bumper guard, substantially as shown.
